UNITED STATES PATENT OFFICE.

WILLIAM P. BARCLAY, OF CHICAGO, ILLINOIS.

VAPOR-CONDENSING APPARATUS.

1,403,282.

Specification of Letters Patent. Patented Jan. 10, 1922.

Application filed April 19, 1920. Serial No. 375,145.

To all whom it may concern:

Be it known that I, WILLIAM PARIS BARCLAY, a citizen of the United States, residing at Chicago, in the county of Cook and 5 State of Illinois, have invented certain new and useful Improvements in Vapor-Condensing Apparatus in Relation to Steam Heating of Buildings.

This invention relates in general to means 10 for condensing the water vapor issuing from a pipe coil system, such as used in buildings for heating purposes.

In steam heating systems, provision is 15 generally made for the return of the water vapor from the pipe coils, or a system of radiators, by the use of a return pipe or pipes that are connected in a suitable manner to a reciprocating pump that ultimately returns the water of condensation back to the 20 steam boiler forming part of the steam heating system of the building.

The rapidly increasing use of electric power in public buildings makes possible a change from a slow moving reciprocating 25 steam pump method to one that will operate at a high speed by the use of a high speed centrifugal or rotary pump, in connection with an ejector-condenser as a part of a high speed system, whereby certain advantages 30 are attained over a slower method.

My new method consists in the combination 35 of a centrifugal pump with an ejector-condenser, whereby the said pump is used to force water as a condensing medium through an ejector-condenser, and condense the vapor supplied to the ejector-condenser, the said centrifugal or rotary pump being actuated by an electric motor preferably direct connected to the pump, and other parts 40 in connection therewith, that will be fully explained in detail.

The original ejector-condenser was conceived and constructed to displace the air pump and condenser of a condensing steam 45 engine or to perform the work thereof, and in its new relation to a steam heating system I have adopted the ejector-principle to condense the vapor from a pipe coil, or radiator heating system, and by causing a 50 rapid circulation of water through the ejector-condenser by a centrifugal or a rotary pump rapid condensation of the vapor occurs on entering the ejector-condenser, and the condensate is instantly ejected into a

water compartment of a tank which is connected with the inlet side, of the centrifugal pump.

In the drawings:

Fig. 1, shows a front elevation partly sectional, of the apparatus. 60

Fig. 2, shows an elevation at a right angle to Fig. 1.

Fig. 3, shows a plan view of the apparatus.

Fig. 4, shows an ejector-condenser 65 adapted to meet its new requirements in relation to the vapor and water compartments of a tank.

Fig. 5, is an exterior elevation of the ejector-condenser. 70

Fig. 6, is a sectional view through line 6, 6, of Fig. 4.

Fig. 7, shows a plan view of the upper head of the ejector-condenser, and parts in relation thereto. 75

Similar letters refer to similar parts throughout the several views.

The base B supports a metal tank C, a centrifugal pump D, and an electric motor E, that the entire apparatus can be easily 80 transported.

The tank C is divided into two compartments by the division plate c³, the compartment c is for water and the compartment c' is for vapor from the return pipe. 85

The centrifugal pump D is preferably driven direct by an electric motor E without any belt or intermediate gear, so as to avoid unnecessary vibration and noise, and the said pump is a means of causing a rapid 90 circulation of water to occur between the water compartment c of the tank C and the interior of the ejector-condenser F, that is attached to the upper head c' of the tank C.

The ejector-condenser F, is shown in enlarged views in Figs. 4, 5, 6, 7, and the sectional view represented in Fig. 6, illustrates the interior construction on line 6, 6, of the ejector-condenser. In an ejector-condenser to have the most efficient operation, the circulated water passing through the ejector-condenser should move downward, so that the circulated water is instantly freed from further obstruction on leaving the lower nozzle 3 of the ejector-condenser. 95

The water inlet port f of the ejector-condenser is for pipe connection with the extreme end of the discharge pipe d of the cen-

trifugal pump D, and the water on entering the ejector-condenser immediately moves downwards, and passes through the nozzles 1, 2, 3, of the ejector-condenser into the water compartment c, of the tank C, for further use as a condensing medium, or as feed water to a steam boiler, according to changeable conditions throughout the heating system.

10 In the discharge pipe d of the pump D there is a Y fitting y and to the lateral branch of this fitting the pipe z which leads to the boiler is connected.

15 The water control stem f' of the ejector-condenser F is used to regulate the amount of water allowed to pass through the ejector-condenser as a condensing medium, and also to entirely shut off the supply of water passing through the nozzles 1, 2, 3, and into the 20 water compartment of the tank C.

25 The water control stem f' of the ejector-condenser is controlled in its action by a float G acting through a stem g that causes the fulcrum lever h pivoted to a post v to alternately rise up and move down and operate through an intermediate link u the lever i that is rigidly attached to a spindle k pivoted to the body of the ejector-condenser.

30 The pivoted spindle k operates the lever r that connects to the water control stem f' of the ejector-condenser.

35 The stem g of the float at its upper end is formed with an oblong opening g' to permit the float G to rise and fall with the water within the compartment c of the tank more or less of a limited distance, without causing the water control stem f' to move either up or down, and the operation of the water control stem is performed during the last few 40 inches of the rise and fall of the water in the compartment c, of the tank C, and when the water in the compartment c of the tank C has reached its highest level, the water control stem f' is then at its lowest position in 45 the nozzle 1 of the ejector-condenser, and the condensing water is then shut off, so that it cannot pass through the ejector-condenser, but the centrifugal pump remains in operation and lowers the water in the compartment c of the tank a greater or less distance by discharging it through the branch g, until the current is cut off that operates the 50 electric motor E.

55 The vapor inlet ports p to the ejector-condenser, permits vapor from the compartment c' of the tank to pass between the nozzles 1, and 2, of the ejector-condenser, and meet the circulated water at the space between the ends of the nozzles 1, and 2.

60 The vapor inlet ports p' of the ejector-condenser permit vapor from the same compartment c to enter the ejector-condenser and pass between the nozzle 2 and the outer wall of the ejector-condenser, and meet the 65 circulated water for vapor condensing pur-

poses between the lower end of nozzle 2 and the upper throat part of the nozzle 3, and from the lower end of nozzle 3, the circulated water, and the water due to vapor condensation is ejected into the water compartment c, of the tank C.

What I claim is:

1. In a condensing apparatus comprising a tank divided into water and vapor compartments, an ejector-condenser attached to the upper head of said tank, an electric motor-driven centrifugal pump with its intake pipe connected to the water compartment of the tank and with its discharge pipe connected to a Y fitting one branch of which is connected to the water inlet port of the ejector-condenser and the other to the feed water pipe of a steam boiler, a float within the water compartment of the tank automatically controlling the nozzle spindle of the 75 ejector-condenser through intermediate parts connected thereto, so that water will be circulated through the ejector condenser as a condensing medium for the vapor inhaled into the ejector-condenser from the vapor compartment of the tank or the water otherwise forced by the 80 circulating pump into the steam boiler of the heating system connected therewith 85 according as the nozzle spindle permits water to circulate through the ejector-condenser or prevents such circulation of water through the ejector-condenser.

2. In a condensing apparatus a tank having vapor and water compartments, an ejector-condenser attached to the upper head of said tank and projecting into and through the vapor compartment of the tank, inlet ports formed in the ejector-condenser for vapor to enter from the vapor compartment 100 of the tank into the ejector-condenser, a centrifugal pump drawing water from the tank connected by way of its discharge pipe to the ejector-condenser, an electric motor connected to the centrifugal pump to operate 105 the said pump, a float in the water compartment of the tank automatically controlling the nozzle spindle of the ejector-condenser through intermediate parts connected therewith, so that the nozzle spindle 110 of the ejector-condenser will permit water to circulate through the ejector-condenser during the operation of the centrifugal pump or entirely shut off such water circulation according to the position occupied by the float in the water compartment of the tank.

3. In a condensing apparatus the combination of a tank, an ejector-condenser mounted thereon, a centrifugal pump pipe connected by way of its inlet with the water compartment of the tank and by way of its discharge branch pipe connected to the ejector-condenser, a float located within the tank 125 controlling the operation of a central stem 130

in the ejector-condenser, whereby an intermittent or a continuous circulation of water will occur through the ejector-condenser.

4. In a condensing apparatus for supplying water to a steam boiler and condensing the vapor from the return pipe coils of a steam heating system, the combination of a tank divided into water and vapor compartments, an ejector-condenser mounted upon the upper head of the tank and reaching through the vapor compartment and into the water compartment of the tank, inlet ports formed in the ejector-condenser for vapor to issue into the ejector-condenser from the vapor compartment of the tank, and the discharge nozzle of the ejector-condenser discharging the circulated water and the water formed by vapor condensation into the water compartment of the tank, and a centrifugal pump having its discharge

connected to a Y fitting whose branches lead to the ejector-condenser and to a boiler.

5. In a condensing apparatus, a tank divided into water and vapor compartments, an ejector-condenser attached to the upper head of the tank, an electric motor driven centrifugal pump having its water intake pipe connected to the water compartment of the tank, a discharge pipe from the centrifugal pump to the inlet water port of the ejector-condenser, a float provided with a stem connected to and operating a horizontal lever *h* pivoted at one end to a support post *v*, an intermediate link *u* connecting the horizontal lever *h* to a lever *i* mounted upon a stem *k* pivoted in the body of the ejector-condenser, and a lever *r* mounted on the stem *k* connecting with the water control stem *f'* of the ejector-condenser.

WILLIAM P. BARCLAY.
